LADDER CONSTRUCTION

Otto J. Brandel, Portland, Oreg.

Application January 11, 1944, Serial No. 517,835

5 Claims. (Cl. 228—29)

This invention relates to ladders and is particularly adapted to folding A-frame ladders.

The primary object of the invention is to provide a folding ladder of considerable rigidity, a ladder that will support scaffolding and the like with safety.

A further object of the invention is to provide a hinge that will permit the folding of the ladder within itself, requiring a minimum amount of storage space.

A still further object of the invention is to provide a hinge that will afford great rigidity and that will hold the frame of the ladder in open position without any locking mechanism, at the same time affording great strength.

These and other incidental objects will be apparent in the drawings, specification and claims.

Referring to the drawings:

Figure 1 illustrates my new and improved ladder in operating position.

Figure 2 illustrates the ladder in inoperative and folded position.

Figure 3 is a fragmentary side elevation of the top and hinged portion of the ladder.

Figure 4 illustrates a fragmentary front view of the ladder, partially broken away for convenience of illustration.

Figure 5 is a fragmentary inverted perspective illustration of the hinged portion of the ladder.

Figure 6 is a fragmentary and sectional detail illustrating a modified form of construction.

In the drawings:

My new and improved ladder 1 consists of usual construction of steps 2 and reinforcing rods 3 assembled together between the side frames 4 and 5. Secured to the upper ends of the frames 4 and 5 are hinged members 6. These members may be secured to the upper ends of the frame 4 and 5 by any suitable means, preferably bolts 7.

The members 6 form part of my invention and have angle portions 8 formed thereon, best illustrated in Figures 4 and 5. These angles are secured to the top step 9 of the ladder by suitable fastening means, as screws or bolts 10. The supporting or bracing frames 11 and 12 of the ladder have hinged members 13 fixed to their upper ends by suitable fastening means, as bolts 14.

A spacer 15, preferably a hollow tube, passes through the openings 16 at the upper end of the ladder frames 4 and 5 and bears against the hinged members 6 and 13 at each of its ends, spacing the side frames of the ladder apart. A tie rod 17 passes through the upper ends of the brace frames 11 and 12 through the members 13 at 18 and the members 6 at 19, as well as the 55

spacer bar 15. The tie rod has a holding nut 20 on one of its ends for tightening the whole assembly together, best illustrated in Figure 4. Providing a spacer between the hinge members 5 and the side frames of the ladder is one of the primary objects of my invention. The cinching up of the hinge portions by the tie rods against the spacer bar provides an assembly of rigid construction, not obtained by using individual self contained hinge members, which has been the construction used before my present construction.

The members 13 have extensions 21 which limit the opening of the ladder in erected position. The extension 21 bears against the angle 8 at 22, providing a rigid stop for limiting the movement of the bracing supports 11 and 12. The pivot point of the hinge members 6 and 13 are located midway the width of the ladder frames, permitting the braces 11 and 12 to embrace the ladder frames 4 and 5 when the ladder is folded, best illustrated in Figure 2. This is an important feature of my invention providing a portable device requiring a minimum of space.

I have found that in using A-frame ladders for scaffolding and the like, that it is most desirable to have a rigidly constructed ladder. In my construction the hinged members 6 are securely fastened to the top 9 through the angles 8, and by employing a spacer 15 in connection with a tie rod 17 further insures rigid construction between the ladder frames 4 and 5 and the braces 11 and 12.

Another object of using the tie rod in connection with the spacer 15 is to be able to bind the whole assembly tightly together so that friction developed between the member 6 and 13 will hold the frames of the ladder in desired fixed position, requiring no other means of holding the ladder in open or closed position.

In Figure 6 I show a modified form of construction, wherein an additional bracing member 23 is secured to the top 9 by the angle 24 and bolts 25. The member 23 is fixedly secured to the ladder members 4 and 5 by any suitable fastening means.

I do not wish to be limited to the exact mechanical construction as illustrated, as other forms of mechanical embodiment may be substituted to carry out the spirit of my claims.

What I claim is:

1. A step ladder, comprising main and bracing frames, each including uprights, one having steps, a hinge-forming element secured to the uprights of the main frame, a cooperating hinge element carried by the uprights of the bracing frame, a hollow spacing member bridging the uprights of

the main frame, extending through such uprights and bearing squarely against the hinge element of such main frame, and a hinge rod extending through the spacing member, uprights of both frames and the hinge elements of the latter, and means for securing the hinge rod.

2. A step ladder, comprising main and bracing frames, each including uprights, one having steps, a hinge-forming element secured to the uprights of the main frame, a cooperating hinge element carried by the uprights of the bracing frame, a hollow spacing member bridging the uprights of the main frame, extending through such uprights and bearing squarely against the hinge element of such main frame, said spacing member providing bracing means between the uprights of both frames having contact bearing between the hinge-forming elements of the main frame uprights.

3. A step ladder, comprising main and bracing frames, each including uprights, one having steps, a hinge-forming element secured to the uprights of the main frame, a cooperating hinge element carried by the uprights of the bracing frame, a hollow spacing member bridging the uprights of the main frame, extending through such uprights and bearing squarely against the hinge element of such main frame, said spacing member providing bracing means between the uprights of both frames having contact bearing between the hinge-forming elements of the main frame uprights, and

means whereby such contact may be tightened to insure rigidity of support at the pivot line.

4. A step ladder, comprising main and bracing frames, each including uprights, one having steps, a hinge-forming element secured to the uprights of the main frame, a cooperating hinge element carried by the uprights of the bracing frame, a hollow spacing member bridging the uprights of the main frame, extending through such uprights and bearing squarely against the hinge element of such main frame, and a hinge rod extending through the spacing member uprights of both frames and the hinge elements of the latter, and means for securing the hinge rod, and cooperating means on the hinge elements of each frame to cooperate to form limiting abutments when the frames are in ladder-forming position.

5. A step ladder, comprising main and bracing frames, metallic elements connected to the respective frames and forming cooperating hinge sections, a pivot rod traversing the main frame and extending through and forming the pivot mounting of the hinge sections, and a brace member surrounding the pivot rod and bearing at its ends squarely against the hinge sections of the main frame, said brace member bridging and extending through the uprights of the main frame, and end tightening means on the pivot rod to maintain the bracing effect of the brace member.
